UNITED STATES PATENT OFFICE.

GEORGE F. SHAVER, OF NEW YORK, N. Y., ASSIGNOR TO HYGIENIC SOAP GRANULATOR COMPANY, A CORPORATION OF NEW JERSEY.

SOAP-SHAVING DEVICE.

983,317.

Specification of Letters Patent.

Patented Feb. 7, 1911.

Application filed September 9, 1905. Serial No. 277,770.

To all whom it may concern:

Be it known that I, GEORGE F. SHAVER, a citizen of the United States, and resident of New York, in the county of New York and State of New York, have invented certain new and useful Improvements in Soap-Shaving Devices, of which the following is a specification.

This invention relates to a device which is primarily designed to be used in connection with a toilet fixture adapted to supply soap in such a form that it may be readily and economically used, such as soap shaving and granulating machines.

It has been found by many experiments with soap shaving machines that much better results are produced when the cake of soap is held against the cutter with a practically uniform pressure as the soap shavings will then be of uniform thickness and the cutter is much less liable to clog and will operate much more smoothly and efficiently under these conditions.

The object of my invention is to provide a device which may be used in connection with soap shaving machines and will hold the cake of soap against the cutter with a practically uniform pressure. To accomplish this result I provide a device which is in the nature of a lazy-tongs or toggle actuated by a spring. One end of the series of toggle levers is fixed in position and the opposite or moving end is adapted to operate against a disk which presses against the cake of soap and holds the same in position against the cutter.

The construction of a soap shaving machine such as I have chosen to illustrate this application of my invention is fully described in my co-pending application Ser. No. 277,769, filed contemporaneously with this one. The same general features of construction are shown in both applications but the distinguishing features embodying this invention will be specifically described herein and definitely defined in the claims.

In the drawings like parts have been given similar reference numbers in each of the figures.

Figure 1 is a cross-section taken on the center line 1—1 of Fig. 2, showing the relative position of the several parts of the device. Fig. 2 is a side elevation of a device

embodying my invention having portions thereof broken away showing part of the interior construction. 55

In the soap shaving device which I have chosen to illustrate my invention in the drawings herewith a vertical soap container 1, is preferably cylindrical in form, constructed of sheet metal and provided with a suitable cover 2. A support or bracket of suitable form may be provided for attaching the device to the wash basin or toilet fixture with which it is to be used. One end of 60 such a bracket is shown at 3 where it projects through the container and is riveted thereto forming a support for a vertical shaft 4 which is adapted to rotate the cutter. A suitable handle and lever such as 6 65 is provided at the upper end of said shaft which projects through a bearing in the cover 2. This bearing is of peculiar construction and is so designed as to prevent any water leaking through the cover to the 70 interior of the container. The construction of this bearing is described in my co-pending application above referred to. 75

A sleeve 7 provides a support to which links 8 and 9 are pivotally attached. A pair 80 of crossed levers 10 and 11, pivoted at their intersection, are pivotally attached to the outer end of the links 8 and 9 respectively, and to the opposite ends of the levers 10 and 11 and second set of crossed levers 12 and 13, also pivotally connected at their intersection, are attached. At the lower end of the levers 12 and 13 are pivotally attached a pair of links 14 and 15 which are in turn 85 pivotally attached to a movable sleeve 16 90 surrounding the shaft.

A guiding sleeve 17 is attached to a disk 5. This disk is adapted to operate against the upper end of a cake of soap 21 to hold the same in engagement with the rotating 95 cutter 22 located at the under side of the cake of soap.

A coil spring 20 surrounds the shaft 4 and is adapted to operate against the lower portion of a tubular member 18 which incloses 100 said spring for a portion of its length, the lower end of said member being so formed as to provide a stop to engage said spring. The upper end of the spring operates against the stop 7 which is attached to the cover 2 105 and is adapted to be compressed between

this stop and the tubular member 18. As this latter member is movable the operation of the spring is to move the same downward.

At the upper end of the movable tubular member 18 a collar 19 is attached and to this collar the crossed levers 10 and 11 are attached at their intersection by a pivotal connection.

The combination of links and levers above described form a lazy-tongs or toggle device and the operation of the spring when under compression is to move the tubular member 18 downward. As the links 8 and 9 are held at their upper end by the sleeve 7 and as the levers 10 and 11 are attached to the aforesaid tubular member 18 by means of the collar 19 at their intersection as described the downward movement of the tubular member 18 will be multiplied or increased by the extension of the lazy tong device. The lower end of the lazy tong device is attached to the sleeve 16 as described and this sleeve operates against the disk 5 to move the same downward against the cake of soap. The maximum downward pressure of the spring 20 corresponds to the uppermost position of the disk 5 and decreases as the disk moves downward. The combination of levers forming a lazy tong device such as described above multiplies the movement caused by the extension of the spring and consequently the necessary movement of the disk can be produced with a much smaller extension of the spring and consequently with a much less difference between the maximum and minimum thrust of the spring than would be possible if the spring operated directly against the disk. It has been found by experiments it is impracticable to use a spring which would give the necessary amount of pressure at the lowest position of the disk and not have too great a pressure at the highest position. This device obviates this difficulty and permits the use of a strong spring of small diameter which takes up much less space and operates through a limited movement, this movement being multiplied to the desired amount by the use of the lazy tong device as already described.

It will be understood that the number and length of the lazy tong levers may be varied to suit the different requirements and will be dependent upon the relative strength of the spring used.

The construction of the cutter and other features of this device are fully described in my co-pending application above referred to and as this device is equally applicable to various designs of soap shaving or granulating machines, it is not thought necessary to describe in detail the construction or the other features of this machine.

The features herein shown and described are intended as an illustration of an operative embodiment of my invention and it will

be evident that the details of construction shown admit of many changes to meet various requirements.

What I claim is:

1. In a soap shaving machine, the combination of a container, a cutter suitably supported therein, means for operating said cutter, a pair of crossed levers pivotally connected at their intersection, a follower, links pivotally attached to said crossed levers and similarly attached to said follower, links pivotally attached to said crossed levers and similarly attached to said container and spring means connecting and constantly operative between said cross levers and said container. 70 75 80

2. In a soap shaving machine, the combination of a container provided with a cover portion, a cutter suitably supported within said casing, a follower located within said casing, a system of levers forming a lazy-tong device interposed between said cover portion and said follower and pivotally connected to each of said parts, a spring seat formed upon said lazy-tong device, a spring 90 seat formed upon said cover portion, and a spring connecting and constantly operative between said seats and normally urging said lazy-tong device extension. 85 90

3. In a soap shaving device, the combination of a container provided with a cover portion, a cutter suitably supported within said container, a follower located within said container, a plurality of levers constructed to constitute a lazy-tong device interposed between said cover portion and said follower, a spring casing carried by said lazy-tong device, and a spring located within said spring casing and connecting and constantly operative between the bottom 100 105 wall thereof and said cover portion.

4. In a soap shaving machine, the combination of a container having a cover portion, a cutter suitably supported within said container, a shaft for operating said cutter, a follower located within said casing, one or more pairs of crossed levers pivotally connected at their intersection and interposed between said cover portion and said container, links connecting each of said last mentioned parts with said crossed levers, a spring seat carried by said crossed levers at their points of intersection, a spring seat carried by said cover portion and an extensible spring interposed between said spring seats. 110 115 120

5. In a soap shaving machine, the combination of a casing provided with a removable cover portion, a cutter mounted to rotate interiorly of said casing, a shaft connected with said cutter and operable from a position exteriorly of said casing, a follower, a plurality of pairs of pivotally connected crossed levers interposed between said follower and said cover portion, the 125 130 135

levers constituting each pair being pivotally connected at their points of intersection, a spring seat supported at the point of intersection of the pair of levers most remote from said follower, and an extensile spring interposed between said spring seat and said cover portion.

6. In a soap shaving machine, the combination of a container having a removable cover portion, a cutter suitably supported for rotation within said container, a shaft extending through said cover portion and operatively engaged with said cutter, a follower positioned upon said shaft, a plurality of pairs of crossed levers pivotally connected at their points of intersection, a lever of each pair being pivotally connected to a lever of another pair, links connecting one pair of said crossed levers with said follower, links connecting another pair of said crossed levers with said cover portion, a spring casing carried by said last mentioned pair of levers at their points of intersection, a spring seat formed upon said cover portion, and a spring located within said spring casing and interposed between a portion thereof and the spring seat of said cover portion.

7. In a soap shaving machine, the combination of a container, a cutter suitably supported within said container, means for operating said cutter, a follower located within said casing, a lazy-tong device located within said casing and interposed between said container and said cover portion, and a spring connecting and constantly operative between said lazy-tong device and said cover portion, said spring exerting its stress in a direction parallel to the direction of extension of said lazy-tong device.

8. In a soap shaving machine, the combination of a container having a removable cover portion, a cutter suitably supported within said container, a shaft extending

through said cover portion and operatively connected with said cutter, a follower positioned upon said shaft, a lazy-tong device arranged at either side of said shaft, links connecting said lazy-tong devices with said follower and said cover portion, a spring casing positioned upon said shaft and supported by said lazy-tong devices, and a spring located within said spring casing and interposed between the bottom wall thereof and said cover portion and urging said lazy-tong devices to extension.

9. In a soap shaving machine, the combination of a container, a cutter, means for operating the cutter, a follower, a pair of crossed levers pivotally connected at their intersection, links pivotally attached to each end of said levers and to the upper end of the container and the follower, respectively, a tubular member forming an intermediate support attached to said levers at their intersection and to the follower, and a spring extensile between and connected to said tubular member and the container.

10. In a soap shaving machine, the combination of a container, a cutter, means for operating said cutter, a pair of crossed levers pivotally connected at their intersection, links pivotally attached to each end of said levers a tubular member forming an intermediate support attached to said levers at their intersection, and resilient means operatively connected to said tubular member to operate the device to hold a cake of soap in position against the cutter.

Signed at New York in the county of New York and State of New York this eighth day of September A. D. 1905.

GEORGE F. SHAVER.
